UNITED STATES PATENT OFFICE.

ALBERT H. TAYLOR, OF WASHINGTON, DISTRICT OF COLUMBIA, ASSIGNEE TO WIRED RADIO, INC., OF NEW YORK, N. Y., A CORPORATION OF DELAWARE.

SIGNAL-TRANSMISSION SYSTEM.

Application filed September 20, 1926. Serial No. 136,701.

My invention relates broadly to high voltage generator in the same range of voltage, namely 220 to 500 for the negative voltage on the grid of the power amplifier when same is used as a frequency multiplier.

5 One of the objects of my invention is to provide a circuit arrangement for a high power electron tube transmitter employing oscillator and power amplifier tubes, wherein a high potential circuit is provided 10 for simultaneously delivering the plate supply voltage for the oscillator tube and the grid biasing potential for the power amplifier tube.

Another object of my invention is to provide 15 a circuit arrangement for an electron tube transmitter employing a piezo electric crystal control circuit for the oscillator of the electron tube system with a power amplifier or frequency multiplier connected 20 to the output circuit of the oscillator with a circuit arrangement for supplying high voltage to the oscillator and biasing potential to the power amplifier or frequency multiplier for facilitating the use of the second and third harmonics of the master 25 oscillator in the power amplifier.

Still another object of my invention is to provide 30 a circuit arrangement for a master oscillator and power amplifier of an electron tube transmission system in which a keying circuit is interposed between the high potential source for the oscillator and the grid circuit of the power amplifier for the transmission of signals under control of a piezo electric crystal frequency control circuit.

My invention will be more clearly understood from the specification hereinafter following by referring to the accompanying drawing which diagrammatically illustrates 40 the principles of my invention in an electron tube transmission system. In connection with the operation of transmitters, particularly high frequency transmitters, and more especially those provided with piezo electric crystal control, it becomes advisable to use on the grid of the power amplifier tube when that tube acts not only as an amplifier but as a frequency multiplier, a very high negative C voltage, which in many cases becomes 45 of the same order of magnitude as the plate voltage on the master oscillator tube. It has been customary hitherto to supply 50 a voltage lying in the range of 220 to 500 volts D. C. to the plate of the master oscillator tube and then to employ a special C

50 By my present invention I employ a special circuit between the electron tube oscillator and power amplifier systems in which there is interposed a source of potential for simultaneously supplying the plate voltage for the master oscillator tube and 55 the biasing potential for the frequency multiplier tube or power amplifier. A circuit connecting the source to the grid of the power amplifier tube may be utilized as the keying circuit for the production of signals. 70 Special provision is made for insulating the filament circuit of the oscillator against the relatively high potentials involved in the system.

Referring to the drawing in more detail, 75 reference character 1 designates the electron tube which functions as an oscillator for the transmission system. The electron tube 1 contains cathode 2, grid electrode 3 and plate electrode 4. A filament transformer 5 is 80 provided for supplying the filament electrodes of the oscillator tube or tubes 1, the filament transformer including a primary winding 6 and a secondary winding 7 especially insulated for withstanding the 85 high potentials involved in this type of circuit, that is of a nature of 500 volts or more. Alternating current may be supplied to the primary winding 6 and for securing smooth operation of the electron tube circuit 90 balancing condensers 9 and 10 are provided on opposite sides of the mid-tap connection 8 on secondary winding 7.

The input circuit of the oscillator has been shown at 11 as including the piezo electric device 12 between the plates 12₁ and 12₂, connected in series with ammeter A₁ and condenser 16 to the input electrodes 2 and 3 of the electron tube 1. The choke coil 14 and battery 15 are arranged in series across the piezo electric crystal circuit as shown. The output circuit of the electron tube 1 delivers high frequency oscillations to the power amplifier or frequency multiplier tube 17. The tube 17 includes filament electrode 18, grid electrode 19 and plate electrode 20. The filament electrode 18 is heated from battery 21 under control of rheostat 22. The input circuit of the frequency multiplier or power amplifier tube 17 is coupled with the output 110

circuit of the oscillator through variable inductance 23 tuned by condenser 25 and coupled through condenser 24 with the plate circuit of tube 1. Ammeter A_2 is arranged 5 in the tuned circuit 23-25 between the power amplifier and oscillator tubes. The output circuit of power amplifier or frequency multiplier tube 17 includes condenser 26 and inductance 27 tuned by variable condenser 28. The high potential for the plate supply circuit of the frequency multiplier or power amplifier is supplied 10 from either an alternating or direct current source. I have successfully used both alternating and direct current in the output circuit of the frequency multiplier tube.

In the drawings I have illustrated an alternating current source 32 and have represented a key 33 in circuit therewith which 20 may interrupt the plate supply circuit for the production of signals. The cathode circuit for the frequency multiplier tube has been shown as connected to a ground or counterpoise at 36. A suitable choke 34 is 25 connected in the high potential supply circuit in series with the plate electrode 20 of the electron tube 17. The output circuit of the power amplifier or frequency multiplier is coupled to the inductance 29 in the 30 antenna ground circuit 30-31.

The circuit of my invention is illustrated between the plate electrode 4 of the oscillator tube 1 and the grid electrode 19 of the power amplifier or frequency multiplier tube 17. 35 This circuit includes a source of direct current 37 having its negative terminal connected through choke coil 40 with grid electrode 19, and having its positive terminal connected through choke coil 39 with plate electrode 4. A signaling key 41 may be 40 interposed in series with this circuit and may be used in lieu of the key 33 for the transmission of signals. The supply of high potential to the output circuit of tube 1 is 45 completed by a connection from the negative side of the source 37 through choke coil 38 with the mid-tap connection 8 of secondary winding 7 of filament transformer 5.

By this circuit arrangement high potential is supplied to the output circuit of tube 1 simultaneously with the biasing of the grid electrode of the tube 17 with a correspondingly high potential. Where it may be desirable to vary the negative C voltage 55 from the source a resistance potentiometer may be placed across the terminals of the machine and an adjustable tap taken from the resistance potentiometer to the grid electrode 19 through choke coil 40 instead of 60 direct to the negative terminal of the machine 37.

The circuit arrangement illustrated has proven to be particularly adapted for piezo electric crystal control transmitters, inasmuch as it is seldom that the piezo electric 65

crystal controlled master oscillator is able to use a voltage of a higher order than that which is necessary for the operation of the frequency multiplier and amplifier. The second and third harmonics of the master 70 oscillator may be brought out in the power amplifier tube by virtue of the circuit arrangement of the present invention. Other harmonics are often present but are not as useful in the frequency multiplier system as 75 are the second and third harmonics. It is important that high insulation be provided in the filament transformer for the protection of the system against breakdown.

While I have described my invention in its 80 preferred embodiment, I desire that it be understood that modifications may be made and that no limitations upon the invention are intended other than are imposed by the scope of the appended claims.

What I claim as new and desire to secure by Letters Patent of the United States is as follows:

1. In a signal transmission system an electron tube oscillator, an electron tube amplification system having its input circuit connected to the output circuit of said oscillator and a high potential source for impressing a positive potential upon the output circuit of said oscillator and a negative potential 95 upon the input circuit of said power amplifier.

2. In a signal transmission system a plurality of electron tubes each having grid, filament and plate electrodes, input and output circuits interconnecting said electrodes, one of said electron tubes being arranged for the production of high frequency oscillations, another of said electron tubes being arranged for the amplification of the oscillations thus produced and a high potential source interposed between the output circuit of said first mentioned electron tube and the input circuit of said second mentioned electron tube for impressing a positive potential upon the plate electrode of said oscillator and impressing negative potential upon the grid electrode of said power amplifier.

3. In a signal transmission system a plurality of electron tubes each having grid, filament and plate electrodes, input and output circuits interconnecting said electrodes, one of said electron tubes functioning for the production of high frequency oscillations and the other of said electron tubes functioning as a power amplifier, a piezo electric crystal connected in the input circuit of said first mentioned electron tube for sustaining oscillations in said circuits at a frequency corresponding to the frequency of said piezo electric crystal element, and a source of potential having a value required for operation with said piezo electric crystal element, said source of potential 130

having its positive terminal connected with the plate electrode of said first mentioned tube and having its negative terminal connected with the grid electrode of said second mentioned tube.

4. In a high frequency signal transmission system a combination of a plurality of electron tubes, each of said tubes having grid, filament and plate electrodes, input and output circuits interconnecting said electrodes, at least one of said tubes functioning as an oscillator and another of said tubes functioning as a power amplifier, means coupling the output of said oscillator with the input of said power amplifier and a circuit interposed between the plate electrode of said oscillator and the grid electrode of said power amplifier, said circuit including a source of potential with choke coils on opposite sides thereof, the negative terminal of

said source connecting with the grid electrode of said power amplifier and the positive terminal of said source connecting with the plate electrode of said oscillator.

5. In a signal transmission system a plurality of electron tubes each having grid, filament and plate electrodes, input and output circuits interconnecting said electrodes, one of said electron tubes operating as an oscillator to generate high frequency oscillations and another of said electron tubes operating as a power amplifier, means coupling the output circuit of said oscillator with the input circuit of said power amplifier, a circuit including a source of direct current, said circuit being connected in inverse order to both the output circuit of said oscillator and the input circuit of said power amplifier.

ALBERT H. TAYLOR.
